CLAIM

The ornamental design for an electronic data transmission band, as shown and described.

DESCRIPTION

The patent or application file contains at least one drawing executed in color. Copies of this patent or patent application publication with color drawing(s) will be provided by the Office upon request and payment of the necessary fee.

1. Electronic data transmission band

1.1 is a perspective view of an electronic data transmission band showing the new design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

The portions of the electronic data transmission band shown in yellow highlight form no part of the claimed design.
